(57) **CLAIM**

The ornamental design for a tool face, as shown and described.

DESCRIPTION

FIG. 1 is a front left perspective view of a tool face.

FIG. 2 is a left side view of the tool face of FIG. 1.

FIG. 3 is a right side view of the tool face of FIG. 1.

FIG. 4 is a front elevational view of the tool face of FIG. 1.

FIG. 5 is a rear elevational view of the tool face of FIG. 1.

FIG. 6 is a top plan view of the tool face of FIG. 1.

FIG. 7 is a bottom plan view of the tool face of FIG. 1; and, FIG. 8 is a front elevational view of the tool face of FIGS. 1-7 illustrating a possible use.

The dashed lines in FIGS. 1-8 are for illustrative purposes only showing environmental subject matter and form no part of the claimed design.

1 Claim, 8 Drawing Sheets
